No. 836,543.

PATENTED NOV. 20, 1906.

W. M. TAYLOR.
AUXILIARY RUDDER.
APPLICATION FILED MAR. 20, 1906.

UNITED STATES PATENT OFFICE.

WILLIAM M. TAYLOR, OF MECKLENBURG COUNTY, VIRGINIA.

AUXILIARY RUDDER.

No. 836,543.

Specification of Letters Patent.

Patented Nov. 20, 1906.

Application filed March 20, 1906. Serial No. 306,989.

To all whom it may concern:

Be it known that I, WILLIAM M. TAYLOR, a citizen of the United States, and a resident of the county of Mecklenburg and State of Virginia, have made certain new and useful Improvements in Auxiliary Rudders, of which the following is a specification.

My invention is an improvement in auxiliary rudders; and it consists in certain novel constructions and combinations of parts hereinafter described and claimed.

Referring to the drawings forming a part hereof, Figure 1 is a side view of a vessel provided with my improved rudder. Fig. 2 is a section on the line 2 2 of Fig. 1, and Fig. 3 is a section on the line 3 3 of Fig. 2.

In the present embodiment of my invention the hull A of the vessel is provided upon each side near the stern thereof with rectangular recesses a.

Frames B, comprising side bars b and an end bar b², are arranged within the recesses, the ends of the side bars being hinged, as at b', to the rear ends of the recesses and the end bar connecting the opposite ends of the side bars being extended beyond the sides thereof, as at b³. The frames B are approximately half the length of the recesses, and the extended ends b³ of the end bars b² are connected by a flexible connection b⁴ with a roller a², journaled vertically within the hull adjacent to the free end of the frame. The flexible connections b⁴ are of a length to permit the free end of the frame to swing outwardly from the hull at an angle of about sixty-five degrees therefrom, and the roller is provided with a weight b⁵, whereby to wind up the flexible connection on the roller when the frame is swung inwardly.

Vanes C, corresponding in length to the length of the recesses and provided at each end with cross-bars c, having extended ends c', are pivotally connected by their centers to the ends of the side bars to swing on their vertical axes.

The extended ends of the cross-bars c have attached thereto flexible connections c², extending through openings in the hull of the ship and connected to rollers a⁴ a⁵, arranged adjacent to the respective ends of the vanes. Upon the shafts of the forward rollers a⁴ are secured cams a³, working through openings in the side of the hull, whereby to press the adjacent end of the vanes outwardly to assist in opening them. A water-tight parti-

tion a' incloses the rollers a² a⁴ a⁵ upon each side of the vessel, and any suitable means may be employed for operating the said rollers; but since such mechanism forms no part of my invention I have not deemed it necessary to describe the same.

In operation when it is desired to steer the ship the roller connected with the front end of the vane on the corresponding side is rotated to loosen the flexible connection, whereby to permit the front end of the vane to swing outwardly, the cam assisting in starting the vane. When it is desired to close the vane, the rear roller a⁵ is loosened, permitting the rear end to be swung outwardly by the force of the water, the flexible connection b⁴ preventing the further outward swinging of the frame. This brings the vane in parallelism with the direction of movement of the water, so that there is no resistance thereon, and the vane may be swung inwardly into its recess, retaining it in parallelism with the side of the hull and with the direction of the force of the water.

By moving the front end of the vane inward, while the rear end is swung outward, the vane is so inclined that the force of the water acts upon the outer side thereof, thus assisting in the closing of the same.

The weight b⁵ is designed to keep the flexible connection b⁴ wound upon its roller and is connected by a cord b⁶, passing over a pulley b⁷ to the roller a², the cord being wound upon the roller in a direction opposite to the winding of the flexible connection b⁴.

What I claim is—

1. The combination with the hull of a ship having a recess upon each side adjacent to the stern, of a frame comprising spaced side bars hinged to the rear end of the recess and connected at their free ends by a cross-bar, the ends of the cross-bar extending beyond the side bars, said frame being approximately half the length of the recess, a fin or vane pivoted by its center on a vertical axis to the free ends of the side bars of the frame, said vane being provided at each end with cross-bars extending beyond the sides thereof, rollers journaled within the hull adjacent to each end of the fin or vane, flexible connections between the rollers and the ends of the vane, a weight-operated roller journaled in the hull adjacent to the free end of the frame, flexible connections of limited length extending between said roller and the extended ends of the vane.

the cross-bar, and cams on sundry of said rollers engaging the ends of the vanes for starting said vanes from the recesses.

2. The combination with the hull of the ship, of frames hinged at their rear ends to the stern thereof, fins pivoted by their centers on a vertical axis within the frame, at the free end thereof, means for limiting the outward movement of the free ends of the frames with respect to the hull, and means for swinging the fins on their pivotal connection with the frame whereby to oppose said fins to the direction of motion of the water or to place them in parallelism therewith.
- 15 3. The combination with the hull of the ship, of vanes in connection therewith, frames hinged to the hull and pivoted to the centers of the vanes whereby to permit said vanes to swing upon a vertical axis, a flexible connection between the free end of the frame and the hull, whereby to limit the outward movement of the vanes with respect to the hull, and means connected with the front and rear ends of the vanes for swinging them on their pivotal connection whereby to incline the vanes with respect to the hull or to place them in parallelism therewith.
- 20 4. The combination with the hull of the ship, of an auxiliary rudder in connection therewith, and comprising vanes connected with said hull by their centers and mounted

to swing on a vertical axis, means for limiting the outward movement of the center of the vanes with respect to the hull, and means connected with the front and rear ends of the vanes for swinging them on their connections with the hull, whereby to place said vanes in an inclined position with respect to the hull or in parallelism therewith.

35 5. The combination with the hull of the ship, of a vane at the rear end thereof, a frame connecting the center of the vane and the hull, means for limiting the outward movement of the vane with respect to the hull, and means for swinging the vane on said connecting means, whereby to oppose said vane to the direction of motion of the water, or to place it in parallelism therewith.

40 6. The combination with the hull of a ship, of an auxiliary rudder, comprising vanes on each side of the hull near the stern thereof, means connecting the centers of the vanes and the hull for retaining said vanes in a substantially vertical plane, means for limiting the outward movement of the center of vane with respect to the hull, and means for swinging the vanes on their connecting means toward and from the hull.

50 WILLIAM M. TAYLOR.
